[57] CLAIM

The ornamental design for a pump handle for use with a biopsy specimen collector, as shown and described.

DESCRIPTION

FIG. 1 is a front perspective view of a pump handle for use with a biopsy specimen collector, showing my new design;

FIG. 2 is a rear perspective view thereof;

FIG. 3 is a side elevational view thereof;

FIG. 4 is a front elevational view thereof;

FIG. 5 is a rear elevational view thereof;

FIG. 6 is a top plan view thereof;

FIG. 7 is a bottom plan view thereof.
